UNITED STATES PATENT OFFICE.

MARK A. HALEY, OF SYRACUSE, NEW YORK, ASSIGNOR TO ONONDAGA POTTERY COMPANY, OF SYRACUSE, NEW YORK, A CORPORATION OF NEW YORK.

DESIGN FOR A TEAPOT.

Application filed November 29, 1922. Serial No. 4,439. Term of patent 14 years.

To all whom it may concern:

Be it known that I, MARK A. HALEY, a citizen of the United States, residing at Syracuse, in the county of Onondaga and State of New York, have invented a new, original, and ornamental Design for Teapot, of which the following is a specification, reference being had to the accompanying drawing, forming a part hereof.

In the drawing, Figs. 1 and 2 are respectively a plan and elevation view of my ornamental design for teapot.

I claim:

The ornamental design for a teapot, substantially as shown.

In testimony whereof, I have hereunto signed my name, at Syracuse, in the county of Onondaga, and State of New York, this 9th day of November, 1922.

MARK A. HALEY.
